DRIVING GEAR FOR ARTIFICIAL SILK
BOBBIN-SPINNING MACHINES

Walter Zinselmeyer, Remscheid-Lennep, Germany, assignor to the firm Barmer Maschinenfabrik Aktiengesellschaft, Wuppertal - Oberbarmen, Germany, a corporation of Germany

Application August 8, 1931, Serial No. 556,021
In Germany September 9, 1930

5 Claims. (Cl. 242—18)

This invention relates to a simplified driving gear for bobbin spinning machines employing a single pair of conical drums.

It is known to employ a pair of conical drums for the drive of bobbin spinning machines in order to produce a uniform drawing out of the thread. In order to produce a variation in the speed of revolution of the bobbins corresponding to the increase in winding diameter, the belt 5 connecting the conical drums is slowly moved along the latter. After the bobbins are fully wound and are replaced by empty bobbins, the belt is moved back to the starting position by hand, whereby the spinning operation is interrupted. It has hitherto been usual therefore, in order to allow of an uninterrupted spinning operation, to employ two pairs of conical drums, alternately setting one pair only in operation while in the case of the other pair the belt is 10 being returned to the starting position by hand.

These arrangements are either uneconomical from the point of view of the time required or, when they are provided with two pairs of drums, of awkward construction.

25 This invention has for its object the provision of a simplified drive for bobbin spinning machines making use only of one pair of conical drums while allowing uninterrupted spinning. The belt which connects the two conical drums 30 is slowly moved, during the spinning operation, along the drums in such a direction that the speed of revolution of the bobbins decreases in accordance with the increase in the winding diameter thereof, whereas during the exchange 35 of the bobbins it is moved back so quickly into the starting position that the spinning operation proceeds without interruption. The movement of the belt in both directions is effected by means of a reversing gear operating through a belt 40 guiding member.

The reversing gear consists of a coupling part loosely mounted on the shaft of an advancing spindle and slowly driven, as for example by means of a pawl- and ratchet mechanism, a 45 second coupling part also loosely mounted on the shaft, but rotating rapidly in the opposite direction to the first, and a change-over coupling arranged to be axially displaceable on but non-rotatable with respect to the said shaft. This 50 change-over coupling is alternately connected to the two coupling parts, whereby the advancing spindle is rotated slowly in the one direction and rapidly in the other direction, so that the belt guide moves slowly in one direction and rapidly in the reverse direction.

In order to effect the change-over a rocking lever is mounted on the change-over coupling and connected with the operating rod by means of a tension spring which, when moved over the dead-point, instantaneously changes over the 5 change-over coupling.

The operating rod may however be held by a detent and stressed by means of a spring shortly before the change-over by the belt guiding member and then allowed to move, for effecting the 10 change-over of the change-over coupling, under the action of the spring, by releasing the detent through the intermediary of an abutment on the belt guiding member.

For entirely automatic operation, the bobbins, mounted on a rocking member, are swung around by means of the operating rod simultaneously with the changing over of the reversing gear. The operating rod, by operating a locking lever, engages a key between the rocking member and the drive, this key being again disengaged automatically by the locking lever after a half rotation. For this purpose the locking lever is provided with two noses arranged diametrically opposite with respect to 20 the rocking member, which noses alternately disengage the key on the rocking of the said member.

In the accompanying drawings, which illustrate two constructions of the apparatus according to the invention,

Fig. 1 is a diagrammatic front elevation view of a driving device for bobbin spinning machines,

Fig. 2 is the same in side elevation,

Fig. 3 illustrates the eccentric drive for the locking lever of the rocking member, being a fragmentary view taken on the line A—B of Fig. 2,

Fig. 4 is a fragmentary plan view of the 40 reversing gear,

Fig. 5 is a front elevational view of a second construction of the operating links for reversing the drive, and

Fig. 6 is a fragmentary plan view of the 45 reversing gear shown in Fig. 5.

The driving arrangement for bobbin spinning machines shown in Figs. 1 and 2 consists of two conical drums 1 and 2, which are so mounted on two superimposed shafts 3 and 4 that their 50 conicities are oppositely directed. The two conical drums 1 and 2 are operatively connected by means of a belt 5. A belt guide, consisting of a fork 6 having two guide rollers 47 arranged at each of its ends, is provided for displacing the 55

belt longitudinally of the drums. For the tensioning of the belt there is arranged on the belt guide, by means of a fork 49, a tensioning roller 48 which is pressed on to the belt by the action 5 of its weight. The belt guide is mounted on a lead screw or advancing spindle 7 and is displaced thereby in the axial direction. Also mounted on the spindle 7, laterally of the drums 1 and 2, is an easily rotatable ratchet wheel 10 which is secured against axial displacement. Immediately adjacent this wheel is mounted, also so as to be freely rotatable, a bell-crank lever 50 which may be oscillated by means of a cam mechanism driven from the gear wheel 32 15 and having its connecting rod 51 secured to one end of the bell-crank lever. At the other end of the bell-crank lever is pivoted a pawl 52 engaging by its nose with the teeth of the ratchet wheel 10. A further toothed wheel 14 is rotatably mounted on the spindle 7, being secured against axial displacement thereon, and is rapidly rotated by means of a drive not shown in the drawings.

Between the two wheels 10 and 14 is mounted 25 a change-over coupling 8, which is arranged to be axially displaceable upon whilst secured against rotation relatively to the spindle 7, by means of a feather and groove arrangement. Parallel with the spindle 7 there is mounted a 30 coupling operating rod 21 which is axially displaceable and carries two stops 22 and 64 for the displacement of the change-over coupling. Moreover this rod 21 is connected with one end of a lever 20, the other end of which is pivotally 35 connected to a support 53. The lever 20 is further connected by a spring 19 with another operating rod 18 mounted below the spindle 7. This rod is axially displaceable and carries two 40 stop rings 16 and 17, against which a stop 15 disposed on the belt guide alternately strikes during the movement of the belt guide.

For the bobbin changing operation the rocking member 54 is connected by means of a key 26 with a driving wheel 27, and is again uncoupled 45 after a rocking movement of 180° has been effected. The driving wheel 27 is rotatably mounted on one end of the rocking member 54 by means of a stub shaft 55. The key 26 is mounted in a groove of the stub shaft 55 and is 50 retained in uncoupled position by means of the nose 56 of a locking lever 25. The locking lever 25, for the purpose of changing the bobbins, is actuated from the rod 21. For this purpose there is provided on the rod 21 an engagement 55 member 58 which drives, through a pawl 22', a ratchet wheel 59. The ratchet wheel 59 is secured to a control plate 23 formed with notches. These notches are alternately spaced a different 60 distance from the axis of rotation. An axially displaceable pin 24, adapted to engage in these notches, is connected with one end of the locking lever 25 and is forced into the notches by means of a spring 60.

The operation of the drive is hereinafter 65 described. Figs. 1 and 2 show the parts at the end of the winding operation, shortly before the exchange of the bobbins. The belt 5, under the action of the belt guide, has reached the end position at the right-hand end of the conical 70 drums. Shortly before this the stop 15 of the belt guide strikes the stop ring 17 of the operating rod 18 and thereby displaces the spring 19 secured on said rod 18 through the dead point, towards the right, into the position shown in 75 Fig. 1. In consequence of this the lever 20 is

5 jerked to the right under the action of the spring 19 and displaces the coupling operating rod 21 which couples the change-over coupling 8 with the spur wheel 14. The advancing spindle 7 is then set in rapid rotation in the reverse direction whereby the belt guide is quickly moved back into the starting position shown in dotted lines in Fig. 1.

Simultaneously with the reversal of the change-over coupling the displacement of the 10 rod 21 rocks the lever 20 which in turn rocks the pawl 22' and advances the control plate 23 so far in relation to the ratchet wheel 59 that the pin 24 rises out of the notch 61 and drops into the notch 62. Hereby the pin 24, under 15 the action of the spring 60, is moved somewhat downwardly and the locking lever 25 is rocked about the pin 63 so that the nose 56 releases the driving key 26. This key 26 is now rotated under the action of the spring 29, whereby the 20 rocking member 54 is coupled with the driving wheel 27 and is rotated until the nose of the key 26 strikes the upper nose 57 of the locking lever 25 and again disengages the driving wheel 27 due to the rotation of the driving key into its 25 initial position.

Shortly, before the belt guide arrives in the position shown in dotted lines, the stop 15 strikes against the other stop ring 16 of the rod 18 and moves the latter to the left, whereby the spring 30 19 is again moved over its dead point, but this time to the left into the position shown in dotted lines. Thereby the lever 20 is jerked back and disengages, by means of the rod 21 and the stop 64, the change-over coupling from the spur 35 wheel 14 and couples it with the ratchet wheel 10. The pawl and ratchet drive 10, 11 now acting on the spindle 7 rotates the latter slowly and thus displaces the belt 5, through the intermediary of the belt guide, in the direction of the 40 arrow a. This motion is executed during winding and serves to reduce the rate of revolution according to the increasing diameter of the windings.

Fig. 5 shows a further construction of the 45 control device for reversing change-over coupling. The rod 18 is omitted and replaced by two sleeves 37 and 38 secured on the coupling operating rod 21 in addition to the stops 22 and 64. Each of these sleeves is provided at one 50 end with a nose 35, 36, whereas at the other end there is secured a spring 39, 40 encircling the rod 21. A stop 34 fixed to the belt guide, which during its movement is displaced longitudinally of the rod 21, alternately compresses 55 the springs shortly before the end position is reached. On a stationary rod 33 arranged above the rod 21 there are arranged, on sleeves 41, 42 disposed approximately opposite to the sleeves 37, 38, detents 43 and 44. Each detent 43 and 44 60 is formed as a two armed lever, one end being shaped to a hook 45 or 46. Each detent is rotatably mounted on a bolt 65 or 66 and during the movement of the coupling operating rod, engages at the end positions alternately behind 65 the nose 35 or 36 of the sleeve 37 or 38. A rod-like stop 32 mounted transversely to the belt guide is adapted to strike alternately, in the end positions, against one of the detents 43 or 44. The detent thus released frees the corresponding 70 sleeve 37 or 38.

The operation of the device will be described with reference to Fig. 5. It being assumed that the belt guide has almost arrived at the end position shown in the figure, the coupling op- 75

erating rod 21 is disposed in its left-hand end position, in which the detent 43 is disengaged and the detent 44 engages with its hook behind the nose 36. Upon the further movement of 5 the belt guide to the right-hand end position the stop 34 strikes against the spring 40 and compresses this until the stop 32 strikes against the inner lever end of the detent 44. This 10 detent is thereby disengaged and releases the sleeve 38 which is immediately moved to the right under the action of the spring 40 and reverses the change-over coupling 8 by means of the abutment mounted on the control rod 21. When the control rod 21 has arrived at its 15 right-hand end position, the hook of the other detent engages behind the nose 35 of the sleeve 37, under the action of a spring (not shown) mounted on the detent. When the belt guide is again moved back to its starting position the 20 operating rod is again stressed so that a rapid change-over motion can take place upon the release of the corresponding detent.

What I claim is:

1. A drive for bobbin spinning machines comprising one pair of conical drums, a belt connecting said drums, a belt guide mounted on an advancing spindle, a slowly rotating coupling part mounted loosely on the shaft of said advancing spindle, a second coupling part also 25 loosely mounted on said shaft, rotating rapidly in the reverse direction, and a change-over coupling axially displaceable but secured against rotation on said shaft, said change-over coupling being located between said coupling parts 30 and movable for selective engagement therewith.

2. A drive for bobbin spinning machines comprising one pair of conical drums, a belt connecting operatively said drums, an advancing spindle, a belt guide mounted on said advancing spindle, a slowly rotating coupling part mounted loosely on the shaft of said advancing spindle, a second coupling part also loosely mounted on said shaft and rapidly rotating in the reverse direction, a change-over coupling 40 axially displaceable but secured against rotation on said shaft, said change-over coupling being located between said coupling parts and movable along said shaft for selective engagement therewith, an operating rod carrying two stops 45 for said belt guide, stops on said rod engageable with said change-over coupling to move the same into selective engagement with said coupling parts, a rocking lever pivoted at said change-over coupling, and a spring connecting 50 said operating rod with the said rocking lever and adapted to be moved suddenly through a dead point.

3. A drive for bobbin spinning machines comprising one pair of conical drums arranged on parallel axes, a belt connecting operatively said drums, an advancing spindle, a belt guide mounted on said advancing spindle and provided with stops, a slowly rotating coupling part mounted loosely on the shaft of the advancing 55 spindle, a second coupling part also loosely mounted on said shaft and rapidly rotating in

the reverse direction, a change-over coupling axially displaceable but secured against rotation on said shaft, said change-over coupling being located between said coupling parts and movable along said shaft for selective engagement therewith, a rod cooperating with said belt guide, means on said rod for operatively connecting said rod with the change-over coupling, springs arranged on said rod, and pawls adapted alternately to stress or to loosen said springs 10 by the action of the stops of the belt guide.

4. A winding mechanism comprising one pair of conical drums arranged on parallel shafts with opposite conicities, a belt connecting operatively said drums, an advancing spindle, a belt guide mounted on said advancing spindle and provided with stops, a slowly rotating coupling part mounted loosely on the shaft of the advancing spindle, a second coupling part also loosely mounted on said shaft and rapidly rotating 15 in the reverse direction, a change-over coupling axially displaceable but secured against rotation on said shaft, said change-over coupling being located between said coupling parts and movable along said shaft for selective engagement therewith, an operating rod actuated from the belt guide for alternately engaging and disengaging said change-over coupling with the slowly or the rapidly rotating coupling part, an intermittently operable rocking member, means 20 to cause operative engagement between said rocking member and the driven one of said shafts, said means being normally held in inoperative position, and means controlled by the movement of said operating rod for intermittently and alternately releasing the last means to effect operating of the rocking member and to effect holding of said last means from operative position.

5. A winding mechanism comprising one pair of conical drums arranged on parallel shafts with opposite conicities, a belt connecting operatively said drums, an advancing spindle, a slowly rotating coupling part mounted loosely on the shaft of the advancing spindle, a second coupling part also loosely mounted on said shaft and rapidly rotating 40 in the reverse direction, a change-over coupling axially displaceable but secured against rotation on said shaft, said change-over coupling being located between said coupling parts and movable along the shaft of the advancing spindle for selective engagement therewith, an intermittently operable rocking member mounted on the driven one of said shafts, a key for effecting keying of said rocking 45 member and shaft into operative relation, an escapement lever normally holding the key from operative keying position and movable to permit rotation of the key through 180 degrees from one position to another, and means controlled by the movement of said operating rod for effecting movement of the escapement lever to release the key for operation of the rocking member intermittently.

WALTER ZINSELMAYER.
